UNITED STATES PATENT OFFICE

DAVID LAMPERT, OF CHICAGO, ILLINOIS, ASSIGNOR TO WILLIAM R. NEUMANN, OF CHICAGO, ILLINOIS

DESIGN FOR A WEDDING RING

Application filed May 31, 1930. Serial No. 35,868. Term of patent 7 years.

To all whom it may concern:

Be it known that I, DAVID LAMPERT, a citizen of the United States, residing at Chicago, in the county of Cook and State of Illinois, have invented a new, original, and ornamental Design for Wedding Rings, of which the following is a specification, reference being had to the accompanying drawing, forming a part thereof, in which—

Fig. 1 is a plan view, and
Fig. 2 is a front elevation showing my new design.

I claim:
The ornamental design for a wedding ring, as shown.

DAVID LAMPERT.
